UNITED STATES PATENT OFFICE.

DONATO PICIULO, OF NEW YORK, N. Y.

DEVICE FOR CUTTING SPAGHETTI.

1,217,341.

Specification of Letters Patent. Patented Feb. 27, 1917.

Application filed April 14, 1915. Serial No. 21,228.

To all whom it may concern:

Be it known that I, DONATO PICIULO, a citizen of the United States, and a resident of the borough of the Bronx, city, county, 5 and State of New York, have invented certain new and useful Improvements in Devices for Cutting Spaghetti, of which the following is a specification.

This invention relates to a device for cutting spaghetti and has for its object a construction for mechanically cutting the spaghetti strands through the medium of a simple and convenient household implement to be hereinafter described.

15 In the accompanying drawings,

Figure 1 represents a plan view of my construction.

Fig. 2 represents a section taken on line 2—2 of Fig. 1.

20 Fig. 3 represents a cross-section taken on line 3—3 of Fig. 1.

Fig. 4 represents a detail of the adjusting means provided in my construction, the same being taken on line 4—4 of Fig. 2.

25 Fig. 5 is a detail of one end of the cross-rod of my construction taken on line 5—5 of Fig. 2.

In the description following, like reference numerals indicate like parts in all the 30 figures.

My construction comprises a frame having a pair of parallel bars 1—1 and a pair of parallel beams 2—2 intermediate of the ends of said parallel bars. These beams 2—2 are 35 preferably secured between and at right angles to the parallel bars 1—1 by means of vertical mortises in said bars, indicated at 3—3, cut on the inner vertical sides of each of said parallel bars 1—1 intermediate their 40 respective ends, such mortises preferably extending downwardly only part-way of the vertical inner sides of said bars, as shown at 4—4 (Fig. 3). In this manner the said beams, which may be dove-tailed, are 45 surely connected to and held by the parallel bars 1—1, without any liability to transverse displacement, due to the strain to which they are subjected by reason of the pressure exerted thereon by the strands hereinafter described. In addition, screws 5—5 50 extending from the outer sides of the parallel bars 1—1 and entering the ends of the parallel beams are employed, in order more rigidly to unite the beams and the parallel bars. As shown in my drawings, each of 55

the parallel bars 1—1 extends some distance beyond its intersection with said beams 2—2, the extensions being indicated at 6—6 and 7—7 of my drawings, and these extensions 6—6 and 7—7 are provided to support, near 60 each of the two ends of the frame, the cross- rods 8 and 9. These cross-rods 8 and 9 are preferably made of metal and their respective ends inserted in oppositely located mortises 8^a and 9^a cut in the extensions 6—6 and 7—7, respectively. These mortises are 65 preferably covered by metal plates 10 and 11, said plates having slots 12 and 13, respectively, to receive the ends of said cross-rods 8 and 9, respectively. 70

The cross-rod 8 is rigidly maintained against movement in the slots 12 of the plates 10 but, for the purpose of adjusting the tension of the strands hereinafter described, the cross-rod 9, on the contrary, is 75 mounted movably in the oppositely located slots 13, which receive the ends of said cross-rod 9, said slots being elongated, as shown at 14, to permit of the necessary extent of transverse movement of the ends of the rod 80 9 therein. Each of the ends of the projections 7—7 is mortised in a longitudinal direction, as indicated at 15, for the reception of the screw studs 16, the ends of said screw studs projecting outwardly through said 85 mortises 15. The inner end of these screw studs 16 is connected to the rod 9 by means, for instance, of an integrally formed block 17 having eyes into which the ends of the cross-rod 9 are adapted to fit. Each outwardly threaded end of the projecting screw studs 16 is provided with a screw nut 18 engaging the thread of said studs 16. 90

Starting from one of said cross rods, for example cross-rod 9, a wire strand 19 (the 95 end of which is made fast upon said cross-rod 9 as indicated at 20) is passed therefrom over the beams 2—2, and to and around the cross-rod 8, and thence passed back over the beams 2—2 and back to the cross-rod 9, 100 and so forth in like manner until the end of the wire is reached, said end then being secured to the cross-rod 9, as indicated at 20^a, or in any other suitable manner. The 105 said strands 19 are equally spaced apart throughout the extent of their active surface, namely between the beams 2—2, and are so maintained equidistant by means of saddles 21—21 secured to the upper surface of each of the beams 2—2, said saddles hav- 110

ing equidistant grooves 22—22 in which the strands 19 are seated.

When it is desired to increase the tension of the strands 19 the turning of the nuts 18 5 will move the screw studs 16 and the cross-rod 9 outwardly along the slots 13 of the plates 11. When my device is not in use, the tension upon the strands 19 may be reduced by the manipulation of the nuts 18 in 10 the opposite direction.

In utilizing my invention, the strands 19 are first adjusted to the desired tension by turning the screw nuts 18 to the right; the sheet of dough then is placed upon the 15 strands 19 and by the application of a roller pin over said sheet of dough said sheet is cut into the desired spaghetti strands which will drop into any appropriate vessel beneath said strands.

20 It will be noted, from the foregoing description, that I have provided a simple and efficient device for the formation of spaghetti and one which is capable of instant mechanical adjustment of the tautness of 25 the cutting strands and one wherein the tautness or the slack in the said strands may be regulated to the finest degree.

The parallel bars and the beams and the saddles for said beams are preferably made 30 of wood although, if desired, they may be formed of any other suitable material. Wood is the preferred material employed because it is cheaper and more easily worked

and is much lighter than would be a metallic structure.

While I have shown my invention in one of many forms in which the same may be utilized, I desire it to be understood that the same may be practised in a variety of modified constructions without departing from 40 the spirit of my invention.

What I claim and desire to secure by Letters Patent is:

A device for cutting spaghetti comprising a frame having a pair of longitudinally extending parallel bars; a pair of intersecting beams rigidly connected to said bars; oppositely located mortises provided near the respective ends of said parallel bars; cross rods extending between the parallel bars and 45 into said oppositely located mortises, one of said cross rods being adapted to slide in its mortises transversely of said parallel bars; a screw and nut mechanism carried by said parallel bars and connected to said sliding 50 cross rod for sliding the cross rod transversely of said parallel bars; a continuous wire strand secured upon said cross rods and passing around said cross rods and back and forth from one to the other thereof, said 55 strand being supported upon the parallel cross beams.

In testimony whereof, I have hereunto set my hand this 12th day of April, 1915.

DONATO PICIULO.

Copies of this patent may be obtained for five cents each, by addressing the "Commissioner of Patents, Washington, D. C."
